QUICK-ACTION SWITCH.

1,349,038.

Specification of Letters Patent. Patented Aug. 10, 1920.

Application filed May 2, 1917. Serial No. 166,062.

To all whom it may concern:

Be it known that we, CARL H. BISSELL and FLOYD C. SMITH, citizens of the United States, and residents of Syracuse, in the county of Onondaga and State of New York, have invented a certain new and useful Quick-Action Switch, of which the following is a specification.

This invention relates to switches and has for its object means by which the movable member of the switch is caused to have a quick action, which means is particularly simple in construction and highly efficient and durable in use; and it consists in the combinations and constructions hereinafter set forth and claimed.

In describing this invention reference is had to the accompanying drawings in which like characters designate corresponding parts in all the views.

Figure 1 is an end elevation of a box or housing inclosing the switch provided with our invention.

Fig. 2 is a cross sectional view through the box and switch mechanism, the mechanism for effecting the quick action of the switch being shown in cross section, and partly in elevation.

Fig. 3 is a fragmentary view similar to that shown in Fig. 2 of the switch mechanism, the operating member being shown in a different position from that shown in Fig. 1.

Fig. 4 is a sectional view on line 4—4, Fig. 2.

Fig. 5 is a fragmentary detail view showing the cams for releasing the locking means and the stop for limiting the turning of the shaft.

Fig. 6 is an inner face view of the barrel of the operating member.

This switch comprises generally, a movable switch member, an operating element, a spring interposed between the operating element and the switch member and arranged to be tensioned by the movement of the operating element, and means for delaying the action of the spring on the switch member until the operating element has been moved a predetermined distance, that is, until it approaches the end of its throw. In this embodiment of our invention, the operating element moves in one direction as forwardly, to turn the switch "on," and in the opposite direction, or rearwardly to

turn the switch "off." In both instances, the spring is tensioned and the operation of the switch member delayed.

1 designates the movable switch member which as here shown includes a cross bar 2 carrying knives 3 which coact with contacts 4, fixed to a suitable insulating base as 6, the knives 3 being here shown as hinged at 7 to the contacts 4. The base 6 may be a panel board, but as here shown it is mounted in a housing or box 8.

12 designates a shaft for operating the switch member 1, this shaft being journaled in a suitable fixed support as a hub 13 on the cover 9 of the box 8, the shaft having a rock arm or crank 14 at its inner end provided with means 15 for detachable securing to the cross bar 2 of the switch. As here shown, the means 15 are jaws embracing the cross bar 2 and facing the axis 7 of the switch, the arrangement being such that the jaws 15 cannot be detached from the cross bar 2 unless the switch is open. As the cover 9 carries the switch, the cover cannot be removed except when the switch is "off." Said shaft 12 is arranged in axial alignment with the pivot 7 of the switch member.

17 designates the operating element or handle and as here shown, this element is mounted concentric with the shaft 12.

18 is a torsion spring coiled about the axis of the shaft 12, and arranged to be tensioned in one direction when the operating element or handle 17 is turned in a forward direction, and to be tensioned in the opposite direction when the handle is operated in a rearward direction. Hence, the spring when tensioned in one direction tends to turn the switch member to its "on" position, and when tensioned in the other direction to turn the switch member to its "off" position.

The operating element 17 is here shown as provided with a barrel 19 having an internal hub 20 mounted upon the shaft 12, and also with internal abutments 21, 22 on the inner wall thereof; and the shaft 12 is provided with a crank having an arm 23 or eccentric shoulder extending parallel to the shaft between the abutments 21, 22. One of these abutments as 21 or 22 extends the full depth of the barrel to accommodate springs of different lengths and the other is located near the closed end of the barrel. The operating element is also formed with means

for operating the shaft in case the spring 18 breaks, and as here shown, this means is a shoulder 19^a arranged on the inner side of the end or head of the barrel in position 5 to pick up the arm 23. This shoulder 19^a is preferably located in position to engage the crank arm 23 and move the switch to its "off" position. The barrel 19 is also formed with an external shoulder 19^b for engaging 10 a fixed point 7^a on the cover and limiting the throw of the handle 17 when operated to shift the switch member to its "on" position. The crank arm 23 is on a disk or plate 24 mounted on the shaft 12 within the inner 15 end of the barrel 19.

The spring 18 is here shown as coiled about the hub 20 which extends from the outer wall of the barrel 19 into the barrel and terminates near the hub of the disk 24, the spring 20 having opposite end portions 25, 26 for normally abutting against the abutments 21, 22, the arm 23 being arranged so that it can be picked up by either one of the end portions 25, 26 when the operating element 25 17 is moved in one direction or the other, and the end portion 25 or 26 that is so picked up is moved away from its abutment 21 or 22 thus causing the spring to be tensioned to tend to turn the shaft.

30 The means for delaying the turning of the shaft 12 when the spring is being tensioned, as here shown includes a lock comprising a spring-pressed bolt 27 slideable in a guide in the hub 18, in a direction parallel to the shaft 12 into and out of spaced apart sockets or perforations 28, 29 in the plate 24, it being arranged in one of said sockets 28, 29 when the switch is "on" and in another socket when the switch is "off." The lock 35 is released after the operating element 17 has been moved a predetermined distance and the spring tensioned in one direction or the other, by means of spaced apart cams 30, 31 on the inner edge of the barrel, these cams 40 coacting with a shoulder or pin 32 projecting laterally from the bolt 27. The movement of the shaft 12 in either direction is limited by a shoulder or lug 33 on the outer face of the disk 24 abutting against shoulders 34 on the hub 18, these shoulders being 45 at the end walls of a cutout in the end face of the hub.

The operating element 17 is held in position by a screw 35 threading into the end of the shaft 12 against a washer 36 which abuts 50 against the outer end of the hub of the operating element 17.

The cover 9 and the barrel 19 are provided with ears 37, 38 having perforations 60 39 for receiving the shackles of padlocks or other locking instruments. The ear 38 on the barrel is always one side or the other of the ear 37 on the cover and a pad lock is attached to each of said ears, and each padlock 65 acts as an obstruction to the ear to

which the other padlock is attached in the well known manner. The keys for the padlocks are kept by different departments of the factory or other place equipped with this switch as will be understood by those 70 skilled in the art.

In operation, assuming that the switch is "off" and the handle 17 is turned to move the switch member 1 to its "on" position, the handle 17 first moves to the right, Fig. 4 75 causing the end 26 of the spring to abut against the crank arm 23 and be moved away from the abutment 22 until the cam 31 engages the pin 32 of the locking bolt 27 and shifts the locking bolt against the action of 80 its spring out of the socket 28 of the plate 24. Thus, the spring 18 is free to move the shaft 12 by reason of its arm 26 coacting on the crank arm 23.

When it is desired to again turn the switch 85 to its "off" position, the handle 17 is moved in a reverse direction causing the end portion 25 of the spring 18 to pick up the crank arm 23 and be held from movement with the operating element while the abutment 21 90 is moving away from said end 25, thus tensioning the spring until the cam 30 engages the shoulder 32 and moves the bolt 27 out of the hole 29 of the plate 24 to permit the spring 18 to transmit its force to the shaft 12. 95

What we claim is:

1. In a quick action switch, the combination of a movable switch member, an operating element movable in reverse directions, a spring interposed between said element and the switch member to transmit the motion of said element, and the operating element having means for acting upon the spring to tension the same in one direction or the other when said element is moved forwardly 100 or rearwardly, means for normally delaying the operation of the switch member in either direction by the spring, means for releasing the former means as the operating element approaches the end of its throw in one direction or the other, and means for limiting the movement of the operating element, substantially as and for the purpose specified.

2. In a quick action switch, the combination of a movable switch member, an oscillating shaft connected to said member, a spring arranged to act in opposite directions on the shaft, an operating element connected to the spring to tension the same to act in one direction or the other on the shaft, and means 115 on the operating member for effecting a positive connection between said member and the shaft in case the spring fails to function on the shaft, substantially as and for the purpose described.

3. In a quick action switch, the combination of a movable switch member, an oscillating shaft connected to said switch member having an eccentric shoulder, a spring arranged to act in opposite directions on the 120 125 130

shoulder, an operating element connected to the spring to tension the same in one direction or the other, means for delaying the action of the spring when under tension on said shoulder, means for operating the delaying means, and means associated with the operating element for coacting with said shoulder to positively move the switch member when the delaying means have been released and the spring fails to act, substantially as and for the purpose specified.

4. In a quick action switch, the combination of a movable switch member, an oscillating shaft connected to said member having an eccentric shoulder, a spring arranged to act in opposite directions on the shoulder, an operating element connected to the spring to tension the same to act in one direction or the other, means for delaying the action of the spring when under tension on said shoulder, and means for operating the delaying means, said element also having a shoulder arranged to engage the former shoulder after the operating element has moved sufficiently to tension the spring and the delaying means has been released, substantially as and for the purpose specified.

5. In a quick action switch, a movable switch member, a shaft connected to the switch member, an operating element mounted on the shaft and including a barrel arranged concentric with the shaft, the barrel having internal spring abutments, a spring coiled about the axis of the shaft within the barrel and having its end portions pressing in opposite directions upon the abutments, a crank mounted on the shaft and having an arm extending in position to engage either of the end portions of the spring and lift the same from said abutments during the operation of said element, means for normally locking the shaft from movement, and means for releasing the locking means, substantially as and for the purpose specified.

6. In a quick action switch, the combination of a movable switch member, a shaft connected to said member, an operating element mounted on the shaft and including a barrel arranged concentric with the shaft and having an axial internal hub on the shaft, the barrel having internal spring abutments, a spring coiled about the hub within the barrel and having its end portions pressing in opposite directions on the abutments, a crank mounted in the barrel on the shaft and having an extension in position to engage either of the end portions of the spring

and lift the same from its abutment, means for normally locking the shaft and the crank from movement, and means for releasing the locking means, the latter means being operated by the operating element, substantially as and for the purpose set forth.

7. In a quick action switch, the combination of a movable switch member, a shaft connected to said member, an operating element mounted on the shaft and having spring abutments, a coiled tension spring carried by the operating element and pressing in opposite directions on the abutments, means associated with the shaft for moving either end portion of the spring away from its abutment during the operation of said element in one direction, a spring pressed lock for normally holding the shaft from movement, said lock being movable in a direction substantially parallel to the axis of the shaft and the cam carried by the operating element for moving the lock out of its operative position after the spring has been tensioned and the operating element has been moved a predetermined distance, substantially as and for the purpose described.

8. In a quick action switch, a support, a movable switch member, a shaft connected to the switch member and journaled in the support, an operating element including a barrel loosely mounted on the shaft, a plate fixed to the shaft within the barrel and having a pair of sockets therein, a crank on the shaft having an eccentric shoulder extending into the barrel parallel to the shaft, the barrel having internal spring abutments on opposite sides of the shoulder and spaced apart therefrom, and also having cams spaced apart on its inner edge, a locking bolt carried by the support and movable into and out of said sockets, the bolt having a shoulder arranged in the path of said cams, and a spring within the barrel and coiled about the axis of the shaft and having opposite end portions coacting with said internal abutments and arranged to be picked up by said eccentric shoulder and thereby cause the spring to be tensioned during the movement of the operating element in one direction or the other, substantially as and for the purpose set forth.

In testimony whereof, we have hereunto signed our names at Syracuse, in the county of Onondaga, and State of New York, this 27th day of April, 1917.

CARL H. BISSELL.
FLOYD C. SMITH.
